CLAIM

The ornamental design for packaging as shown and described.

DESCRIPTION

FIG. 1 is a perspective view of packaging in a first state showing our new design;

FIG. 2 is front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1;

FIG. 7 is a bottom view of the design shown in FIG. 1;

FIG. 8 is a perspective view of packaging in a second state showing our new design;

FIG. 9 is front view of the design shown in FIG. 8;

FIG. 10 is a rear view of the design shown in FIG. 8;

FIG. 11 is a left side view of the design shown in FIG. 8;

FIG. 12 is a right side view of the design shown in FIG. 8;

FIG. 13 is a top view of the design shown in FIG. 8; and,

FIG. 14 is a bottom view of the design shown in FIG. 8.

The evenly-spaced broken lines in the Figures illustrate portions of the packaging that form no part of the claimed design.
